United States Patent Office.

SHEPLY H. WALLACE, OF PARNASSUS, PENNSYLVANIA.

Letters Patent No. 70,298, dated October 29, 1867.

IMPROVEMENT IN MINERS' PICKS.

The Schedule referred to in these Letters Patent and making part of the same.

TO ALL WHOM IT MAY CONCERN:

Be it known that I, SHEPLY H. WALLACE, of Parnassus, in the county of Westmoreland, and State of Pennsylvania, have invented a new and useful Improvement in Picks for Mining Purposes; and I do hereby declare the following to be a full, clear, and exact description thereof, reference being had to the accompanying drawings, making a part of this specification, in which—

Figure 1 is a side view of my improved pick, and

Figure 2 is a sectional view, formed by a plane passing longitudinally through the head and along the line of the handle.

Like letters of reference indicate like parts.

The nature of my invention consists in the construction of a pick for mining purposes, having a head and points so attached to the parts with which they are respectively connected, as to be easily removed for repairs, or that others, either new or old, may be substituted in lieu thereof.

To enable others skilled in the art to make and use my invention, I will proceed to describe its construction and mode of operation.

a is a pick-handle, to which is attached, by the scales *b*, a tenon, *c*, fitting into a mortise in the pick-head *d*, and securely fastened therein by a screw, *e*, with its head countersunk in one side, and held by a screw-thread in the other side of the pick-head *d*. This head *d* is of any desirable size or weight, and of any known form in common use, except that it has removable steel points *f*, such points each having a shank or tenon, *i*, fitting into a corresponding mortise in either end of the head *d*, and secured there by screws *e'*, with countersunk heads and screw-threads, in like manner as above stated.

Riveting, or other equivalent mode of securing the head *d* on its tenon *c*, and the points *f* to the head *d*, may be used in lieu thereof, or the shanks or tenons *i* may be made round and chased and screwed into the ends of the head *d*, which is then bored and tapped for that purpose. But this mode of fastening the points is objectionable, for the reason that the points are liable to become unscrewed by the prying motion which such picks in actual use are apt to receive.

Miners' picks, it is well known, when in use, have frequently to be pointed or sharpened, which involves loss of time to the miner, and injury to the pick-handle in heating the head to remove and refit it; so much so that pick-handles are often spoiled by a few heatings. By my invention the miner can provide himself with one, two, or more extra points for each sized pick-head which he is using, and with no other tool than a screw-driver, or hammer and punch, if rivets be used, change or renew the points at pleasure. The principal causes of delay are thus avoided. The same advantage exists when picks are from any cause broken or otherwise injured.

Pick-heads of different weights are also sometimes needed for different purposes in mining, the work "bearing in" not requiring so heavy a pick as "knocking down." For this reason, and on account of the necessity of frequent sharpening, each miner, in order to work with rapidity, has to supply himself with a complete outfit of picks, which consists usually of six picks, weighing in the aggregate about thirty pounds. By my invention pick-heads may be changed at pleasure, so as to admit of different heads being used on the same handle. I thus reduce the outfit required to two handles and three heads, and avoid the necessity which miners are often under of selling their picks at a considerable loss, on account of the difficulty of carrying them when moving from one bank to another.

Hence, what I claim as my invention, and desire to secure by Letters Patent, is—

Making the head or points, or both head and points of picks for mining purposes, removable, substantially, as and for the purposes hereinbefore set forth.

In testimony whereof I, the said SHEPLY H. WALLACE, have hereunto set my hand in presence of—

Witnesses:

A. S. NICHOLSON,
GEO. H. CHRISTY.

SHEPLY H. WALLACE.
